UNITED STATES PATENT OFFICE.

WILLIAM S. HUTCHINSON, OF OYSTER BAY, NEW YORK.

DRUM-BRAKE.

1,192,523.

Specification of Letters Patent. Patented July 25, 1916.

Application filed August 4, 1915. Serial No. 43,691.

To all whom it may concern:

Be it known that I, WILLIAM S. HUTCHINSON, a citizen of the United States, and a resident of Oyster Bay, Nassau county, New York, have invented a new and useful Improvement in Drum-Brakes, of which the following is a full, clear, and exact description.

My invention relates to improvements in drum brakes and especially to brakes of this character which are applied to automobiles, though obviously the brake can be used on any vehicle or in connection with any rotary member which it is desired to brake.

15 The object of my invention is to produce an exceedingly simple and strong brake mechanism which can be applied readily to the rim of an ordinary drum, and which is constructed and arranged so that when an inner shoe with which the drum is fitted, frictionally engages the rim, such frictional contact will cause the brake mechanism to throw the shoe with great force against the rim of the drum, and so check the speed of 20 the latter and the parts connected therewith.

25 My invention is also intended to produce a structure of this character which will work easily whether the drum is rotating in one direction or the other. In carrying out this idea I provide an expandible shoe which is preferably concentric with the rim of the drum, and arranged just within the latter and at necessary intervals on the shoe I 30 place blocks or members having inclined inner faces which converge toward each other forming essentially a V shaped groove in the inner face of each block, and have an abutment which is preferably a roller in the 35 V of the block or member, and so when the shoe contacts with the drum rim and is moved with the latter in either direction, it will cause the inclined face of the block or member attached to the shoe to ride upon the 40 stationary abutment and so force the shoe firmly against the rim of the drum. This 45 will be understood clearly from the description which follows.

50 Reference is to be had to the accompanying drawings forming a part of this specification, in which similar reference characters indicate corresponding parts in all the views.

55 Figure 1 is a cross section through the axle of a wheeled vehicle having the usual form of drum and shows the brake mecha-

nism in elevation, and Fig. 2 is a broken section at right angles to the view illustrated in Fig. 1.

The drum 10 can be of any usual or preferred construction, and has a rim 11 of the usual type, and I have shown a drum rigidly connected with the hub 12 of the vehicle wheel, the hub having the customary connection with the axle 13. All this, however, 60 has nothing to do with my invention, which relates to the means for bringing a strong brake action against the rim 11, which may be any rotary member whatever.

Within the rim 11 is a shoe 14 which preferably extends over nearly all the inner surface of the rim and is expandible, or at least it has a movement back and forth with relation to the rim. I prefer to make it of a length to nearly encircle the rim as stated, 70 and to connect the adjacent ends of the shoe with an expandible spring 15. A shoe of this kind is also generally provided with a strengthening rib 14a.

The shoe is thrown into frictional engagement with the rim 11 or removed from such frictional engagement by a lever mechanism 16. This I do not show or describe in detail, for so far as the purposes of this invention are concerned, any means can be 80 employed for bringing the shoe into frictional engagement with the rim or for removing it from such engagement.

At intervals on the inner side of the shoe 14 are blocks or members 17 which preferably straddle the rib 14a and each block has two inclined faces 18 on the inner side which converge toward each other, and which normally lie with the apex of the inclined groove walls in contact with an abutment 19 which is stationary so far as its position is concerned with relation to the rim but which for ease of operation is preferably a roller supported on a stationary bearing. As 90 shown each roller is supported on a stud 20, and the latter is secured to the plate 21 which is arranged opposite the open end of the drum 10 and is supported on the housing 22 of the axle 13, though it can be supported in any convenient or preferred manner.

100 It will be seen that when by reason of the lever mechanism 16 or other equivalent mechanism, the shoe is expanded so as to contact with the rim 11, the shoe will start 110 to move with the rim, and this will cause the correspondingly inclined faces 18 of the

several blocks or members 17 to move along the abutments 19, thus forcing the shoe into positive and frictional engagement with the rim 11, and it will be noticed that this action will occur without regard to the direction of rotation of the said rim. It will be seen that this arrangement is of the utmost simplicity and strength, and that any desired braking effect can be had. For instance if the inclined faces 18 are relatively sharp, the braking action will be quick but not so strong, while if the inclined faces have a slight pitch, the action will be slower but much stronger. It will be further observed that the arrangement of the members 17 and abutments 19 is such that the shoe 14 is always held in place and in proper relation to the rim 11.

I claim:

- 20 1. A brake comprising a rotatable member, a shoe arranged within and adjacent to said rotatable member, means for moving the shoe into and out of frictional engagement with said rotatable member, a block on the shoe thinnest near its central portion and with oppositely inclined faces converging toward such central portion, and a stationary abutment opposite and in contact with the inclined faces.
- 25 2. A brake comprising a rotating member, an expansible shoe substantially concentric with said member and within the same, means for expanding and contracting the shoe, blocks spaced apart on the inner portion of the shoe, said blocks being thinned near the central part and having oppositely inclined faces converging toward said central part, and abutments having fixed relation to the shoe rim and arranged

to extend opposite the inclined faces of the 40 blocks.

3. The combination of a rotatable member, a shoe arranged within the member and adapted to impinge against the same, means for moving the shoe into and out of frictional engagement with the rotatable member, inclined faces on the shoe, said faces converging toward each other, and a roller journaled on a stationary support and lying opposite said inclined faces. 45

4. A brake comprising a rotatable member, an expansible shoe substantially concentric with and lying within said member, means for expanding and contracting the shoe, blocks secured to the shoe and having inner inclined faces, the faces of each block converging toward the shoe, and rollers supported by stationary supports and lying opposite the inclined faces of the several blocks. 50

5. A brake comprising a rotatable member, a shoe arranged within the said member and having an inclined plane on the back thereof, and a roller mounted on a stationary support and lying opposite said inclined plane. 55

6. A brake comprising a rotatable member, a shoe arranged within the said member and adapted to frictionally engage said member, inclined planes of opposite pitch 70 arranged on the inner or back part of the shoe, and roller abutments on stationary supports opposite said inclined planes. 65
